(57) **CLAIM**

The ornamental design for a pivoting sign holder for a light pole, as shown and described.

DESCRIPTION

FIG. 1 is a top-front-right perspective view of the first embodiment of a pivoting sign holder for a light pole, showing my new design;

FIG. 2 is a bottom-front-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left-side elevational view thereof;

FIG. 8 is a right-side elevational view thereof;

FIG. 9 is a top-front-right perspective exploded view thereof; and,

FIG. 10 is a front elevational view of the second embodiment of a pivoting sign holder for a light pole.

The broken lines in the drawings depict environment and form no part of the claimed design. In FIG. 10, the article is shown with a symbolic break in its length. The appearance of any portion of the article between the break lines forms no part of the claimed design.
